UNITED STATES PATENT OFFICE

CHARLES E. EASTMAN, OF DES MOINES, IOWA

CONCRETE BUILDING STRUCTURE

Application filed March 5, 1929. Serial No. 344,420.

The object of my invention is to provide a concrete building structure of simple, durable and inexpensive construction in which there is employed for the facings or exposed surfaces thin panels of glass, tile or stone, or the like, and which are permanently and firmly bonded to the completed building structure.

A further object is to provide a structure of this character having a high degree of heat insulating quality and being moisture-proof.

A further object is to provide a structure of this character in which the shrinkage caused by the initial set of the concrete will not be transmitted to the surface ashlar, and hence will have no tendency to transmit checks or cracks.

A further object is to provide a structure of this character in which reinforcing rods are placed both vertically and horizontally at any desired points throughout the structure to meet the requirements of reinforcement.

A further object is to provide a building structure of this character in which an inner and an outer ashlar for forming the surfaces of a concrete wall may be flexibly united at distances properly spaced apart so that when being laid in a wall, both ashlars may be conveniently and easily moved by the operator to positions parallel with the wall surfaces prior to the insertion of the concrete mixture for forming the body of the wall.

A further object is to provide a new method of constructing concrete walls by means of which the ashlars, comprising finished wall surfaces such for instance as glass, may be readily, quickly and easily laid in position by unskilled labor, and then firmly and permanently united to the concrete wall, and the wall reinforced by reinforcing rods arranged either vertically or horizontally in any place throughout the structure.

My invention consists in the construction, arrangement and combination of the various parts of the building wall, and in the method of erecting same, as hereinafter more fully set forth, pointed out in my claims, and illus-

trated in the accompanying drawings, in which:

Figure 1 shows an isometric view of an ashlar unit forming part of my structure.

Figure 2 shows an isometric view of a portion of a finished wall embodying my invention.

Figure 3 shows a transverse, vertical, sectional view through a portion of a concrete wall embodying my invention.

Figure 4 shows a top or plan view of a portion of a finished wall embodying my invention and illustrating a corner therein.

Figure 5 shows a detail, vertical, sectional view of a modified form of building structure embodying my improved ashlars as used in a ceiling construction, upon wooden beams; and

Figure 6 shows a similar view showing the application of my improved ashlars to an I-beam ceiling structure.

Referring to the accompanying drawings, I have used, the reference numeral 10 to indicate the surface panel or ashlar unit. I preferably make this panel of glass on account of its cheapness, weather resisting qualities, and because it lends itself to a wide range of decorative effects. In some instances I employ opaque or translucent glass which may be purchased in various colors and tints, and also in either smooth or rough surfaces. When transparent glass is used, the inner surface is painted and obviously this may be done cheaply and any desired color or decorative effect may be obtained. I have also employed tile and thin slabs of cut stone for this purpose.

On the inner side of the surface ashlar member I apply a coating of a moisture-proof plaster bond 11, having the quality of remaining somewhat elastic and of adhering to the surface panel. Then upon this plaster bond layer 11 I apply a layer 12 comprising a mixture of cement, sand, saw dust, cork or the like, to form a heat insulating layer, the thickness of which depends on the climatic conditions where the building structure is to be used. In extremely cold climates the layer should be relatively thick.

Before the mixture, comprising the layer 10

11, has set or hardened, I place near the corners thereof staples 13 with their end portions extended outwardly away from each other. These are forced into the mixture with their ends 14 resting flat against the plaster bond layer 11, as shown in Figure 1, so that the looped ends thereof are all substantially the same distance from the surface panel 10.

10 Then on the inner surface of the insulating layer 12, I apply another coat of plaster bond material 15. I then connect two of these ashlar units with wires 16 passed through the staples 13, as shown in Figure 15. These wires hold the two ashlar units at approximately the proper distance spaced apart from each other, but permits either of the ashlar units to be moved or tilted slightly relative to the other, for purposes 20 hereinafter made clear. The two ashlar units thus connected form a mould unit for receiving the concrete wall body.

In erecting a concrete wall, a layer of mould units is first placed in proper position. 25 Then the space between them is partly filled with an ordinary concrete mixture, and while the mixture is being filled in, reinforcing rods 17 may be placed in position vertically, and other reinforcing rods 18 may be placed in 30 position horizontally at any point throughout the structure. This feature is very advantageous in that the reinforcements may be accurately spaced to meet the requirements of the wall reinforcement.

35 When the concrete material forming the wall body is placed between the two ashlar units, as shown in Figure 3, and is still in plastic condition, then the operator may readily and easily move one or both of the 40 ashlar units to position in proper alignment within the wall, and since the concrete wall body forms an initial set very quickly, the ashlar units will soon be firmly and immovably held in proper position in the wall.

45 When the insulating layer 12 is applied to the inner side of the surface panel, it will of course contract while setting. However, the tacky or elastic condition of the plaster bond layer 11 will permit such contraction 50 without effecting the surface panel 10, and the ashlar units are permitted to fully set and harden before being built into a wall.

When the concrete material forming the wall body is placed between the ashlars in 55 plastic condition, it will, during its final setting and hardening, contract to a certain extent. This contraction will have no effect upon the ashlars because the plastic bond layer 15 will permit a slight movement of 60 the concrete wall body relative to the ashlar units. This contraction, however, will, because of the reinforcing rods, be localized in its nature and will result in slight checks and cracks throughout the body of the concrete 65 wall when it has taken its final set, but these

will not in any way be transmitted to the ashlar units.

From the foregoing it will be seen that I have provided a building structure that is inexpensive and yet having a high degree of ornamental value, and being capable of wide variations and ornamental treatment. The structure is fireproof and moisture-proof, and I have repeatedly tested the structure under wide variations of temperature, and in 75 extremely cold climates, and have found that no appreciable quantity of moisture can penetrate the wall, and that no condensation of moisture or sweating will take place upon either surface when one surface is exposed to 80 extremely warm temperatures and the opposite surface is exposed to extremely cold temperatures.

The ashlar units can be manufactured with almost absolute accuracy and uniformity in 85 size, because the panels of glass and stone may be cut cheaply by machinery, and then the various other layers forming the ashlar unit may be applied and fitted to the others. After the completed wall has set and hardened, the spaces between the surface units 90 10 may be filled with neat cement or the like flush with the surface.

In the modified form illustrated in Figure 5, I have shown the manner in which my improved ashlars may be employed in ceiling structures. The wooden beam is indicated by the numeral 19, and the ashlar units are laid against the under surfaces of the beams 19 and temporarily held thereto by wires 20 connected to nails 21 in the beam and the adjacent staples 13 in the ashlars. 100

Then a layer of concrete 22 is applied on top of these ashlars to form a bond therewith and through the wires 20 to firmly fix the 105 concrete layer 22 to the beam.

In Figure 6 I have shown a modified form in which the wires 20 are passed over the top of T-beams 23. Otherwise the construction is the same as that shown in Figure 5. 110

In practice with my improved method, I construct the ashlar units by taking first a surface unit of given size and shape and applying to it the several plaster bonding and heat insulating units, and setting the staples in the insulating unit before it has set and hardened, and by this method the contraction of the heat insulating unit is not transmitted to the surface unit, so there can be no danger of cracking the surface unit during such contraction of the heat insulating material, and by setting the staples in the manner herein defined, a firm connection is made with the ashlar unit without in any way mechanically connecting them to the surface units. 115 120 125

By connecting the two ashlar units with wires and in a flexible manner, I am enabled in building a wall to utilize the two ashlar units as a sort of mould for the concrete wall, and then by partly filling the space between 130 135

the two ashlar units with plastic concrete, I am enabled to move either of the ashlar units to proper position in alinement in the wall, and when it is moved to have the concrete wall material quickly form an initial set, which 5 will bond the ashlars to it with the assistance of the connecting wires 16, in such manner that inexperienced persons may readily and quickly learn to properly aline both outer surfaces of the wall and to place both vertical and horizontal reinforcing rods in position at 10 any point throughout the entire area of the building wall.

I claim as my invention:

15 1. In a building structure, an ashlar unit comprising a surface panel, a layer of tacky and flexible material applied to the inner surface thereof, and a layer of heat insulating concrete material applied to the inner surface 20 of the tacky and flexible material, for the purposes stated.

25 2. In a building structure, an ashlar unit comprising a surface panel, a layer of plaster bond material applied to the inner surface thereof, a layer of heat insulating concrete material applied to the inner surface of the plaster bond, and connecting devices 30 embedded in the concrete layer.

35 3. In a building structure, an ashlar unit comprising a surface panel, a layer of plaster bond material applied to the inner surface thereof, a layer of heat insulating concrete material applied to the inner surface of the plaster bond, and connecting devices 40 embedded in the concrete layer, said devices comprising metallic staples having outwardly extended ends and being forced into the concrete material when in plastic condition to position with the ends in engagement with the plaster bond layer, and whereby the inner ends of all of said connecting devices are 45 equally spaced apart from the outer panel.

50 4. In a building structure, an ashlar unit comprising a surface panel, a layer of tacky and flexible material applied to the inner surface thereof, a layer of heat insulating concrete material applied to the inner surface of the tacky and flexible material, and a second layer of tacky and flexible material applied to the inner face of the concrete layer.

55 5. In a building structure, an ashlar unit comprising a surface panel, a layer of tacky and flexible material applied to the inner surface thereof, and a layer of concrete material applied to the inner surface of said tacky and flexible material.

CHARLES E. EASTMAN.
